UNITED STATES PATENT OFFICE

GARRISON BABCOCK, OF SEATTLE, WASHINGTON, ASSIGNOR TO AMERICAN TELE-
CHRONOMETER COMPANY

TELEPHONE INSTRUMENT

Application filed September 11, 1926. Serial No. 134,801.

This invention relates to telephone instruments, more particularly of the class often termed "micro telephone" i. e. a combination instrument in which the transmitter and receiver are mounted upon a common handle.

Heretofore, such instruments have been supported upon a separate base and the closing of the telephone circuit has generally been accomplished by a switch in said separate base operated by the weight of the instrument.

Another form of such combination instrument with which I am familiar has a switch in the handle operated by the grasp of the hand of the user.

In accordance with the preferred form of the present invention, I dispense with the separate stand which is frequently a nuisance. I provide a supporting base directly upon the combination instrument to permit it to stand vertical with the receiver uppermost. Thus it occupies a minimum of desk space and is in convenient position to be grasped by the hand of the user.

25 In order to switch automatically the telephone circuit, I provide contacts which are controlled by the weight of the instrument or a part thereof.

In one form of my invention, I provide a lost motion connection between the upper part and the lower part of the instrument. When the instrument is picked up by grasping the handle, which in this case forms a portion of the upper part, the circuit is switched to

35 closed condition. Upon replacing the instrument upon the table or otherwise supporting the instrument thru its lower part, the circuit is switched automatically to open condition.

40 It is also possible to have the circuit controlled by a switch in a suitable support or stand upon which the base of the instrument seats when the instrument is not in use. This base is appreciably larger than the upper portion of the instrument and its upper surface is inclined downwardly and outwardly from the upper portion and supports the transmitter at an inclination and in proper relation to the receiver to be readily spoken into. The instrument thus supports itself in

upright position so as to be readily grasped with the receiver and transmitter disposed in approximately the position they assume when using the instrument. By providing the base carrying the transmitter and the upper portion extending therefrom and carrying the receiver, I impart to the instrument as a whole a substantially symmetrical and neat and attractive appearance.

In the drawing:

Figure 1 is an elevation of the instrument; Fig. 2 is a side view of the instrument partly in section;

Fig. 3 is a fragmentary sectional view through a modified form of the instrument;

Fig. 4 is a fragmentary vertical sectional view, parts being shown in elevation, of a second modified form of the instrument;

Fig. 5 is a section taken substantially on line 5-5 of Fig. 4; and

Fig. 6 is a fragmentary vertical section through a third modified form of the instrument.

The instrument includes a base 1 of approximately frusto-spherical shape which is closed at its lower end by a disc 2 provided with a covering of felt 3 or other suitable cushioning material. A pedestal 4 is slidably connected to base 1 for limited vertical movement and is provided at its upper end with an enlargement forming a casing 5 within which is mounted a receiver 6 of known construction. The pedestal and the base may be of any suitable material but preferably are made of a synthetic resin, such as a phenolic condensation product, as this material possesses very appreciable mechanical strength while having high electrical insulating properties and being of light weight.

By using this material I am enabled to produce a base and pedestal which present a neat and attractive appearance and possess the requisite mechanical strength while also being much lighter than the base and pedestal commonly used in instruments of this character.

A tube 7 is secured in a reduced neck 8 at the upper end of base 1 and slidably receives a sleeve 9 secured in the lower end of pedestal 4. A screw 10 passes thru slots 11

extending longitudinally of tube 7 and is threaded thru a nut 12 anchored in the pedestal. This screw also passes thru a block or plug 13 secured in the tube. A rod 14 is secured in block 13 and depends therefrom, this rod being provided at its lower end with a rounded head 15 which contacts with a leaf spring 16 of a switch structure 17 secured within base 1. This structure includes 5 silent strips 18, electrically insulated from each other and provided with contact points 19 which coact with the strips and with spring 16 for closing the circuit of the instrument when the spring 16 is released.

15 The base 1 is provided, at its upper portion, with an annular outwardly extending flange 20 which is disposed substantially in alignment with casing 5 but is arranged at an inclination downwardly away from the pedestal 4. A transmitter 21 of known construction is mounted within the base and within flange 20 thereof, this transmitter being also disposed at an inclination so as to be arranged in correct position to talk into the 25 same when the receiver is positioned at the ear of the user. The receiver and the transmitter of the instrument are connected into a circuit which includes the circuit closing and opening switch 17, for which purpose the base 30 is provided with an opening 22 which accommodates a cable carrying the usual wires or conductors. This connection of the switch or circuit controlling means and the receiver and transmitter is well known in this art and 35 need not be illustrated or described in detail. The base also provides a suitable container or housing for an induction coil 23 such as is commonly used in instruments of this general character. It will be apparent from Fig. 40 2 that, when the instrument is in its normal condition and rests upon a desk or other supporting structure, the weight of pedestal 4 and the parts carried thereby is transmitted to spring 16 by means of rod 14 and head 45 15 thus holding the spring 16 depressed so as to open the switch 17 thus opening the circuit of the instrument. Preferably, tho not necessarily, I provide a cushioning ring 24 of felt or other suitable material above the tube 50 7 the lower end of pedestal 4 normally resting upon this ring. When the instrument is removed or raised from the desk for use it is grasped by pedestal 4 so that this pedestal is raised a sufficient distance to release spring 55 16 permitting sufficient upward movement of this spring to close the circuit thru the structure 17, after which upward movement of pedestal 4 relative to the base is positively limited by the screw 10 contacting with the 60 tube 7 at the upper ends of slots 11, after which the base will be raised with the pedestal so as to position the receiver 6 at the user's ear, the transmitter 21 being disposed adjacent the user's mouth. When the instrument 65 15 is again replaced on the desk, the pedestal 4

will be moved downwardly by gravity and the weight of the pedestal and the parts carried thereby will again return the spring 16 to depressed position thus breaking the circuit of the instrument.

In the modified form illustrated in Fig. 3, the pedestal 4A is formed integrally with the base 1A and a sleeve 25 is slidably mounted on the pedestal for vertical movement. A pin 26 is secured in this sleeve and passes thru slots 27 provided in the pedestal and extending longitudinally thereof. This pin also passes thru an eye 28A at the upper end of a rod 28, the lower end of which is secured thru the inner end of a leaf spring 16A of the switch structure 17. In this form, the spring 16A exerts a downward pull on rod 28 which, combined with the weight of the sleeve 25 serves to maintain the switch in circuit opening condition. In using the instrument the sleeve 25 provides a grip or handle which is moved upwardly along the pedestal 4A in the act of raising the instrument thus permitting or causing the spring 16A to be moved into position to close the circuit of the instrument thru the switch structure. When the instrument is returned to normal inoperative position with the base resting upon the desk or other supporting structure the spring 16A is returned to circuit opening position rendering the instrument inoperative.

15 In the form illustrated in Figs. 4 and 5, the pedestal 30 is provided with a depending sleeve 31 which fits snugly about a neck 32 extending from base 1. Preferably, though not necessarily, a cushioning member 33 of felt or other suitable material is disposed between the lower end of pedestal 30 and the upper end of neck 32. A tube 34 of metal or other suitable material is secured in neck 32 by being molded therein, this tube having its lower portion 34A flared. A second tube 35 is slidably mounted through tube 34 and houses the wires 36 which are connected at their lower ends to elements 37 and 38 of the circuit switch structure. A bumper cap 39 is secured on the lower end of tube 35 by a pin 40 or in any other suitable or preferred manner and is provided with suitable openings 41 accommodating the wires 36. A switch button 42 of hard rubber or any other suitable electrical insulating material is secured in the cap 39 and bears upon the inner portion of switch member 37 normally holding the switch open. When the instrument is raised for use by grasping the pedestal 30, the cap 39 is raised relative to switch member 30 thus permitting closing of the switch and rendering the instrument active in the manner previously described. It will be noted that the tubes 34 and 35 are of non-circular cross section, these tubes being illustrated as of square cross section, or any other suitable or preferred form of tube other than circular.

may be employed for this purpose. By having the tubes of non-circular cross section, the pedestal and the base are held against relative turning movement insuring that the 5 receiver and transmitter are held in proper alignment as previously described. It will also be noted that these tubes provide a loose sliding connection between the two sections of the supporting structure while preventing 10 excessive looseness or play in the connections.

In instruments of this general type in which the receiver and the transmitter are mounted in a supporting structure which is rigid and continuous, difficulty is frequently 15 experienced in that howling is caused due to vibrations transmitted through the receiving structure to the transmitter from the receiver or vice versa. An important feature of my invention is the loose connection between 20 the section of the supporting structure which supports the receiver and the section which carries the transmitter. This loose connection serves to effectually prevent any appreciable acoustic continuity between the 25 receiver and the transmitter eliminating the difficulty referred to resulting from transference of vibrations through the supporting structure. Under ordinary conditions, the loose connection between the pedestal and 30 the base is sufficient to prevent howling and provides an amply sufficient interruption or discontinuation of acoustic connection between the section carrying the receiver and the section carrying the transmitter. As a 35 further precaution, however, in the form illustrated in Fig. 4, I provide a cushion member 43 in the form of a felt ring at the top of the bumper cap 39. When the instrument is in use, this ring bears against the flared 40 lower portion 34A of tube 34 and, due to its cushioning properties very effectually eliminates vibration of the base or tube 34 due to vibrations transmitted from the receiver and vice versa. In the form illustrated in 45 Fig. 6, I have shown the tube 34 as provided with a lining 44 of felt or other suitable material. This felt lining, in conjunction with the felt washer 33 and the felt packing member 43, serves to completely cushion the 50 connection between the pedestal and the neck of the base, thus very effectually preventing any acoustic continuity between the receiver and the transmitter so as to effectually eliminate all possibility of vibration of the receiver being transmitted to the transmitter or vice versa. This form of the instrument is very efficient and effectually eliminates all tendency to howl. Under ordinary conditions, such thorough cushioning of the 55 connections between the two sections of the supporting structure is not necessary.

What I claim is:—

1. In an instrument of the character described, a supporting structure including a 60 base and a pedestal connected to the base for

vertical movement relative thereto, a receiver carried by the pedestal, a transmitter carried by the base, a switch for controlling the circuit of the receiver and transmitter carried by the base, and means actuated by movement of the pedestal for closing the switch when the pedestal is raised in the act of grasping the same and raising the instrument and opening the switch when the pedestal is lowered into normal position by the act of returning the instrument to rest upon a desk or other support. 70

2. In an instrument of the character described, a base, a pedestal connected to the base for vertical movement relative thereto, 80 a receiver carried by the pedestal, a transmitter carried by the base, a switch for controlling the receiver and transmitter circuit carried by the base, said switch including a spring and circuit closing members actuated thereby, and means connected to the pedestal and acting to hold the spring in inoperative position when the pedestal is in lowered position relative to the base, the spring being moved into operative position when the pedestal is raised relative to the base. 85

3. In an instrument of the character described, a base, a pedestal connected to the base for vertical movement relative thereto, means for limiting movement of the pedestal in either direction, a receiver carried by the pedestal, a transmitter carried by the base, a switch for controlling the receiver and transmitter circuits carried by the base, the switch including a spring and members actuated thereby for closing the circuit, said members being in open position when the spring is depressed, and a member connected to the pedestal for movement therewith and normally bearing on the spring to hold the same depressed, said member being raised into inoperative position to release the spring when the pedestal is raised relative to the base. 95

4. In an instrument of the character described, a supporting structure and a base, 110 a receiver carried by the supporting structure, a transmitter carried by the base, a tubular member extending from the base, a sleeve-like portion of said supporting structure slidably mounted on the tubular member 115 and having limited vertical movement thereon, a switch for controlling the transmitter and receiver circuit mounted in the base, said switch including contacts moved into operative relation when the base and structure are moved to one limit of their relative motion, and moved into inoperative relation when the base and structure are at the other limit of their relative motion, and a connection between the switch and said supporting 120 structure for controlling said switch by the relative movement of the supporting structure and base. 125

5. In an instrument of the character described, a supporting structure including 130

two relatively movable sections and cushioning connections disposed between and acting in the direction of relative movement between said sections, a receiver carried by one section, and a transmitter carried by the other section.

6. In an instrument of the character described, a supporting structure including two slidably connected sections, the connections 10 between the sections being cushioned in the direction of relative movement between the sections, a receiver carried by one section, a transmitter carried by the other section, and means controlled by movement of the sections toward and away from each other for 15 rendering the receiver and transmitter circuit active and inactive.

In witness whereof, I hereunto subscribe my name this 10th day of August, 1926.
